UNITED STATES PATENT OFFICE.

ABRAHAM M. YEAKEL, OF PERKASIE, PENNSYLVANIA.

WATCHCASE-PENDANT.

SPECIFICATION forming part of Letters Patent No. 621,887, dated March 28, 1899.

Application filed May 25, 1898. Serial No. 681,704. (No model.)

To all whom it may concern:

Be it known that I, ABRAHAM M. YEAKEL, a citizen of the United States, residing at Perkasie, in the county of Bucks, State of Pennsylvania, have invented a new and useful Improvement in Watch-Stems, which improvement is fully set forth in the following specification and accompanying drawings.

My invention consists of a watch stem or arbor which is adapted to be adjusted relatively to the lifting-spring and the winding mechanism and to retain its adjustment, adapting also the length of said stem to be adjusted relatively to the crown, the novel features being hereinafter described, and pointed out in the claim that follows the specification.

Figure 1 represents a side elevation of a watch-stem embodying my invention. Fig. 2 represents a longitudinal section thereof, including a stem, crown, and lifting-spring. Fig. 3 represents a section or portion of another form of stem that may be employed.

Similar letters of reference indicate corresponding parts in the figures.

Referring to the drawings, A designates the pendant-stem or winding-bar of a watch; B, the pendant; C, the crown; D, the spring of the cap, and H the screw, which is passed laterally through the pendant into the interior thereof.

E designates a loose collar on the stem A below the screw H in abutment with the latter.

G^X designates a shoulder in the base of the pendant, the lower portion of said stem A passing through said shoulder. Interposed

between said shoulder G^X and the collar E and abutting thereagainst is the spring K, whose tendency is to elevate said collar and hold it at all times against the screw H regardless of the movement of the stem, and thus rattling of the latter and of the connected parts is prevented.

When the adjustment of parts is effected, should a portion of the stem above the screw H be too long it may be clipped or cut off to the desired extent, so that the crown C occupies the proper position on the pendant without requiring the disarrangement or further manipulation of the nuts to effect the adjustment of said crown.

In Fig. 3 the stem is shown as a female when such is required in lieu of the form of the other figures.

Having thus described my invention, what I claim as new, and desire to secure by Letters Patent, is—

In a device of the character stated, a crown, a stem, a pendant, a shoulder in the base of said pendant through which said stem passes, and a screw laterally entering said pendant above said shoulder, in combination with a collar loosely mounted on said stem below said screw, and a spring interposed between said shoulder and collar adapted to constantly press the latter upwardly against said screw.

ABRAHAM M. YEAKEL.
